TOWEL DISPENSING APPARATUS

Frank F. Pulver, St. Petersburg, Fla., and William H. Matthews, Rochester, N. Y., assignors to Alliance Investment Corporation, St. Petersburg, Fla., a corporation of Florida

Application November 6, 1941, Serial No. 418,862

11 Claims. (Cl. 312—38)

Our invention relates in general to towel cabinets and, more particularly, to towel dispensing apparatus adapted to deliver a pre-determined length of towel to the user and wind up a corresponding length of soiled towel within the cabinet.

Another object of the invention is to provide a towel dispensing cabinet so constructed and arranged that the clean towel is protected from contact with the dirty portions of the toweling and protected against dust and dirt.

Another object of the invention is to provide a towel dispensing cabinet having a compartment so constructed and arranged within the cabinet that the clean toweling is protected from dust and dirt, the compartment being arranged so that the major portion of the dirt, accumulating within the cabinet, drops freely out of the cabinet.

Another object of our invention is to provide a towel cabinet which has inner and outer sections so arranged that the inner section, together with the toweling and dispensing mechanism, therefor, may be removed as a unit from the outer section for the purpose of cleaning the cabinet and adjusting and cleaning the dispensing mechanism.

Another object of the invention is to provide improved means for tensioning and smoothing the web of toweling as it passes over the clean towel feed roll and also as it passes to the soiled towel take up roll.

A further object of the invention is to provide improved and simplified means for pre-determining the length of towel withdrawn for use upon each actuation of the dispensing mechanism.

Still another object of the invention is to provide a cabinet structure the parts of which are so constructed and arranged that the soiled toweling may be quickly removed from the cabinet and so that a clean bolt of toweling may be threaded in the cabinet quickly and without error even by unskilled persons.

Our invention further contemplates the provision of a cabinet structure for dispensing toweling arranged so that when the cabinet door is closed the feed rolls are locked against rotation in one direction while, when the door is open, the feed rolls may be rotated in either direction so as to permit easy adjustment of the toweling, rethreading of the same in case of error, or withdrawal of the toweling from the cabinet in either direction.

Other objects and advantages of the invention

will be particularly pointed out in the claims and will appear from the following description, when taken in connection with the accompanying drawings, in which:

5 Fig. 1 is a front elevation of the towel dispensing cabinet of the invention with the cabinet door closed;

10 Fig. 2 is a side elevation of the cabinet structure, shown in Fig. 1, with parts thereof in dotted lines and a portion of the cabinet structure broken away better to illustrate the invention;

15 Fig. 3 is an enlarged view of a portion of Fig. 2 with the cabinet door open;

20 Fig. 4 is a front elevation of the towel dispensing mechanism partly in section, and shows the general arrangement of the towel feed rolls and illustrates the manner in which the dispensing mechanism is supported within the cabinet structure;

25 Fig. 5 is a top plan view of Fig. 4 with the outer cabinet removed and with the parts in towel dispensing position;

30 Fig. 6 is a fragmentary view of a portion of Fig. 5 with the parts in towel threading or cabinet loading position;

35 Fig. 7 is a view showing the stop mechanism for the towel feed rolls and showing the parts in abutting or feed roll arresting relation;

30 Fig. 8 is a view similar to Fig. 7 showing the position of the parts when the stop pin has been withdrawn from engagement with the stop;

35 Fig. 9 is a vertical section through the dispensing mechanism showing the position of the parts when the machine is loaded and ready for use;

40 Fig. 10 is a view, similar to Fig. 9, showing the parts of the dispensing mechanism in the position they occupy during the towel threading operation, the web of toweling being shown in the position it occupies at the start of towel threading and

45 Fig. 11 is an enlarged view of a portion of Fig. 10 showing the position of the parts and the toweling when the threading operation is substantially completed.

The towel dispensing apparatus of the invention comprises a cabinet, or outer shell section generally indicated by the numeral 12, having 50 top and bottom walls 13, a rear wall 14, side walls 15, and a front opening. The front opening may be closed by a closure or door 16, hinged to one of the side walls, as indicated at 17. The door may be provided with a lock 18 and preferably with a mirror 19. While we have shown a

particular type of cabinet, it will be appreciated that the details of the cabinet may be varied and that the towel dispensing mechanism may be mounted in other styles and shapes of cabinets. The particular cabinet shown is intended for mounting, by means of suitable openings in the back wall 14 (Fig. 4), on suitable supports 21 provided on the wall of a wash room or other place in which the cabinet is to be used.

Mounted within the outer section of the cabinet is an inner section or mechanism supporting frame, generally indicated by the numeral 22 (Fig. 4). The inner section may comprise a pair of side plates 23, having outwardly turned side flanges, as indicated at 24, which are rigidly connected by cross pieces 26, welded or otherwise secured to the side plates. The inner rear wall of the outer cabinet section is provided with a pair of slide clips or latches 27, having ends 28 adapted, when the inner frame section is positioned within the cabinet, to over-lie the upper ends of flanges 24. After the latches have been shifted into position, as permitted by the pin and slot arrangement shown at 25, they may be locked in position by means of thumb screws 29.

As will more clearly appear from Fig. 9, the forward portion of the bottom wall 13 of the cabinet is provided with an elongated slot or opening 31 which matches with a similar slot formed at the door margin. The slots 30 and 31 form an elongated opening through which the web of toweling, indicated by the numeral 32, may depend. The edges of the slots may be upwardly turned, as indicated at 33, to provide smooth surfaces over which the web of toweling may pass.

The rear portion of the lower wall 13 of the cabinet may be provided with a slot 34 upwardly through which the toweling is passed. The opening 34 is made sufficiently wide to permit the attendant who services the cabinet to extend his hand upward into the cabinet for the purpose of threading the toweling, as will more clearly appear later. The edges of the opening 34 are upwardly turned, as indicated at 36, to provide smooth surfaces in case they should be engaged by the web of toweling.

The forward upturned edge further provides an abutment 37 behind which a guide or partition plate 38 may be lodged, when the inner frame section is assembled within the outer cabinet section. It will be apparent, when the frame section is mounted within the cabinet section with the partition plate 38 lodged behind the abutment 37 and with the latches 27 in operative position, that the inner frame section is rigidly locked within the cabinet against any shifting movement.

Carried by the side plates 23 of the inner frame section 22 are a pair of feed rolls 41 and 42 (Fig. 4). The feed rolls are suitably journaled in the side plates and are provided with carborundum or other friction surfaces 43, as is well known in the art to which this invention applies. While any suitable arrangement of the feed rolls may be employed, we prefer to mount the feed rolls approximately vertically one above the other, the lower feed roll 41, in this instance, serving as a clean towel feed roll while the upper feed roll 42 serves as a soiled towel feed roll.

The bottom of the inner frame section is provided with a plate 44 (Fig. 9) which may be curved or flat, as desired, for the reception of a bolt 46 of clean toweling. The inner walls of

the side plates are provided with guide members 47 which are sloped downward and inward, as shown most clearly in Fig. 4 for the purpose of centrally locating the bolt and aligning the web of toweling with respect to the clean towel feed roll 41.

In the preferred form of the invention the clean toweling is passed upward and around the clean towel feed roll 41 and thence forward over a bar 48, and thence downward through the opening formed by the slots 30 and 31 to form a loop beneath the cabinet. The web is then passed upward through the opening 34 to a soiled towel take up roll 49, the function and operation of which will be later described. It will now be apparent, when the toweling is threaded as shown in Fig. 9, that upon the user grasping the depending end of the towel webbing and exerting a downward pull that the clean towel feed roll 41 will be rotated.

Referring now to Figs. 7 and 8, it will be observed that the clean towel feed roll shaft projects through the side plates and has mounted adjacent the left projecting end thereof a driving gear element 51. The shaft ends of the dirty towel feed roll 42 also extend through the side plates and the left projecting end has mounted thereon a gear element 52. The gears 51 and 52 mesh with each other, are of the same diameter, and are provided with the same number of gear teeth, thus insuring a complete rotation of the dirty towel feed roll each time the clean towel feed roll is rotated through one revolution.

It is desired that the apparatus be adapted to dispense a pre-determined length of toweling upon the user pulling downward upon the towel webbing depending from the cabinet. This length of toweling is pre-determined by the circumference of the feed rolls provided that the rotation of the feed rolls is stopped or interrupted upon each complete rotation thereof.

For the purpose of interrupting rotation of the feed rolls the gear 52 is provided with a boss 53. The boss 53 has a bore 54 in which is slidably mounted a piston or pin 56. The pin 56 is free in the bore and has a portion 57 between its ends of decreased diameter for the reception of a screw 58. The screw serves to limit the inward and outward movement of the pin 56 which, as is apparent, will be thrown outward by centrifugal force when the gear 52 is rotated.

A stop 61 is carried by the side plate 23 and is located in the path of movement of the pin 56 when the pin is in its outer position, as shown in Fig. 7. Thus at each rotation of the gear 52, following a pull on the towel webbing, the pin 56 is thrown outward so as to strike the stop or abutment 61 and arrest rotation of the feed rolls. By thus arresting the rotation of the rolls, the user is deterred from using an unnecessary length of toweling. While a timing device might be provided by employing an air cylinder back of the pin or piston with a bleed opening, we prefer the arrangement shown. We have found that where timing devices are employed the user frequently becomes impatient and attempts to forcibly pull and tear the toweling before the timing device has an opportunity to operate.

It will be particularly noted that the stop 61 is located so that the feed rolls are brought to rest with the pin 56 in a vertical position. It is intended that the pin shall drop out of abutting relation by gravity so that the user may, if necessary, obtain additional toweling or subsequent users may actuate the apparatus for the purpose

of obtaining clean toweling. It will be appreciated, if the parts are in the abutting relation shown in Fig. 7, that the pin 56 may not drop by gravity out of position due to its frictional engagement with the stop or abutment 61.

To insure that the pin will drop by gravity the gears are given a slight rotation in the opposite direction after the pin strikes the abutment. This is accomplished by a cam element 62 which is pivoted to the side plate, as indicated at 63. A roller 64 mounted on the inner side surface of the gear 51 is arranged to engage the cam surface 66 when the gear 51 is rotated. A spring 67 having one end abutting against a pin 68 and its other end engaging the cam element, as indicated at 69, normally urges the cam element 62 in a clockwise direction, as viewed in Fig. 7. A stop 71 secured to the side plate limits the movement of the cam element 62.

In the position of the parts shown in Fig. 8, the pin 56 is out of engagement with the stop 61 so that the user may pull downward on the web and secure a measured length of toweling. Upon completion of rotation the parts are in the position shown in Fig. 7 with the mechanism stopped by reason of the engagement of the pin 56 with the stop or abutment 61. In moving to this position the roller 64 (Fig. 7) has cocked the cam element 62 so that when the parts are stopped the spring 67 is tensioned. This causes a force tending to rotate the gear 51 in a counterclockwise direction. It results in a slight rotation of the gears 51 and 52 to the position of the parts shown in Fig. 8 so as to withdraw the pin 56 from the engagement with the abutment 61 and permit the pin 56 to drop by gravity. Thus the parts are conditioned for the next actuation by a user pulling downward on the depending towel webbing.

It is intended when the machine is in operation, for a purpose which will later appear, that rotation of the gears shall be permitted in only one direction (the direction indicated by the arrows in Figs. 7 and 8). However, at times, it is desired to rotate the feed rolls in the opposite direction. For this purpose a cam finger 72 is provided which will permit the gears to be rotated in the reverse direction, from that indicated in the arrows in the Figs. 7 and 8, without interruption by engagement of the pin 56 with a stop.

For preventing rotation of the feed rolls when the machine is in operation, in any direction except that indicated by the arrows in Figs. 7 and 8, the shaft, at the opposite end of the soiled towel feed roll 42, is provided with a ratchet wheel 76 which is adapted to be engaged by a pivoted pawl or detent 77. The pawl 77 has an arm 78 which is engaged by the end 79 of a lever 81 fulcrumed at 82. As shown most clearly in Figs. 9 and 10, the lever 81 projects forwardly through the flange of the side plate 23 into a position such that it may be engaged by the inner wall of the door or closure 16 when the door is closed, as shown at 80 in Fig. 2.

When the door is closed the projecting end of the lever 81 is pushed inward so as to rotate the lever about the pivot 82 in a clockwise direction, as viewed in Fig. 3, and withdraw the end 79 from the pawl. Upon withdrawal of the lever 81, the pawl, which is properly weighted, may drop by gravity into engagement with the teeth of the ratchet wheel 76. It will be appreciated that there is enough play between the teeth of the ratchet wheel 76 and the pawl 77 to permit the slight rotation of the gear 52 (Fig. 7) in a clock-

wise direction required to free the pin 56 from engagement with the stop or abutment 61.

By the ratchet and pawl arrangement, above described, it will be apparent, when the door 16 is closed and locked, that unauthorized persons can not reverse the direction of rotation of the feed rolls so as to pull the towel out of the cabinet. When the machine is loaded or threaded, a certain amount of the toweling is wound upon the take up roll 49. Since, when the door is closed, the direction of the rotation of the feed rolls can not be reversed, from the direction indicated in Fig. 9, the toweling can not be withdrawn from the cabinet by pulling the toweling off the soiled towel take up roll.

One of the important features of our invention lies in the means provided for protecting the clean towel from contact with the dirty toweling and also for protecting the bolt of clean toweling from dust and dirt which may sift downward through the cabinet. For this purpose the bolt of clean toweling is mounted in a separate compartment formed by the plate 44, the partition plate 38, and a shield 91. The shield 91 is bent forward and upward and extends substantially completely across the cabinet between the side plates so that dust and dirt dropping downward from the dirty toweling may fall upon the shield 91 and thence may drop to the rear and outward through the opening 34 in the bottom of the cabinet.

The shield 91 is pivoted so that it may be shifted to the dotted line, as shown in Fig. 10, in which position of the shield the threading of the toweling around the clean towel feed roll may be easily accomplished. The shield 91 further serves the purpose of smoothing the toweling as it passes over the clean towel feed roll and of applying a slight pressure on the toweling so as to maintain the web in contact with the clean towel feed roll. While the shield 91 may be pressed downward by means of a spring, it has been found that the weight thereof, with the pivot point located in the position shown, is sufficient for the purpose desired. The shield 91 thus serves not only to protect the clean toweling but also as a tensioning and smoothing member.

The clean towel feed roll is preferably provided with a second combined tensioning and smoothing plate or member, indicated by the numeral 93. The member 93 is curved in cross section and preferably shrouds the major portion of the circumference of the clean towel feed roll. The curved member 93 is carried by brackets 94 pivoted in the side plates and is normally urged, by means of a spring 96 which extends through an opening adjacent the side edge of lip 101 of member 93, in a direction such that its forward surface 97 engages the web of toweling and presses it against the clean towel feed roll.

It will be observed that a downward pull on the web of toweling will tend to shift the member 93 in a clockwise direction about the pivot 94. For the purpose of arresting this movement a stop pin 98 is provided which in normal operation has no function. However, should the user exert an unnecessarily hard downward pull on the web 32 the member 93 will engage the stop pin 98. Preferably the curved member 93 is slightly flexible, so that should the toweling be pulled vigorously the rear edge 95 will not bear too heavily against the feed roll but instead will exert a resilient pressure on the toweling to press it against the roll.

In Fig. 10 we have shown the apparatus in the

position which the parts occupy at the initial step of threading the towel about the clean towel feed roll. The end of the towel is placed over the curved lip 101 of the plate 93 with the end thereof in contact with the clean towel feed roll. To accomplish this the member 93 may be shifted downward about its pivot so as to lie substantially in engagement with the pin 98. The dirty towel feed roll may then be rotated by hand in a counterclockwise direction so as to rotate the clean towel feed roll in a clockwise direction and thereby feed the web of the toweling around with the clean towel feed roll. With the rotation of the roll the member 93 functions to smoothen and straighten the towel as the roll is rotated. When the end of the toweling has substantially completed a rotation with the roll, the end thereof projects beneath the shield 91. Upon raising the shield the end of the toweling may be grasped and pulled through, draped over the top of the bar 48 to hang downward through the slot 31. A substantial loop of toweling is left dangling below the cabinet while the end of the towel is fed up through the opening 31. This is accomplished by inserting the hand upward between the partition plate 38 and the back wall of the cabinet. The towel is then threaded over a tensioning assembly, generally indicated by the numeral 102, the operation of which will be presently described and rolled upon the soiled towel take up roll 48.

It will be particularly noted that the spring 96 tends to rotate the member 93 so as to cause the web to be pressed against the clean towel feed roll substantially at the point of entrance of the web into engagement with the clean towel feed roll. It will further be noted that the pressure of the shield 91 is exerted on the towel substantially at the point where the towel leaves the feed roll. Thus the towel is tensioned, smoothed and wrapped in contact with substantially the entire circumference of the feed roll so as to prevent slippage and insure proper feeding. Moreover, when the towel is pulled downward, the member 93 pivots and the part 95 of the member 93 presses the webbing, preferably resiliently, against the feed roll.

It is extremely important that the dirty toweling shall accumulate on the soiled towel take up roll 49 by tightly and smoothly winding the webbing thereon. For this purpose, we have provided the novel previously mentioned, web tensioning assembly, generally indicated by the numeral 102. The tensioning assembly 102 comprises a pair of arms 103 which are pivoted, one to each of the side plates as indicated at 104, and connected by a cross plate 106 extending substantially completely across the machine between the side plates. Carried by the forward portions of the arms is a roller 107 which is arranged to rotate freely in openings provided in the arms. Pivoted at the end of each of the arms 103 is one of a pair of swinging arms 108. The free ends of the swinging arms 108 are provided with pins adapted to freely receive a roller 109. If desired, the rollers 107 and 109 may be fixed in their supports. When the rollers are fixed in their supports, the friction on the toweling is increased and hence the web is wound more tightly on the takeup roll.

It will now be appreciated that when the plate 106 is manually swung upward, by means of a finger opening 111 provided in the plate 106, to the position shown in Fig. 11 that the rollers 107 and 109 will assume the position shown in that view. In this position the roller 109 rests loosely against the soiled towel feed roll.

The end of the toweling may then be threaded upward over a bar 112, over the roller 109 and beneath the roller 107. The take up roll during the threading operation is mounted in a pair of grooves 113 provided in the side plates. It will be understood that the take up roll has pins projecting from the ends thereof adapted to be received in the grooves 113 and in the slots 114.

After a suitable length of toweling has been wound on the take up roll, in the manner illustrated in Fig. 11, the take up roll is, while continuing to wind the toweling thereon, placed in the slots 114 and shifted to the position shown in Fig. 9. In this position the dirty toweling rests upon and is driven by the dirty towel feed roll. After the threading operation has been completed, the plate 106, together with the arms 103, is pushed downward to applying tension on the webbing.

For the purpose of guiding the rolls 107 and 109 to their proper position, a pair of cam tracks 116 are provided, one mounted on each of the side plates. These cam tracks are spaced apart a distance just sufficient to accommodate the width of the web and therefore function as a guide to align the web properly with respect to the take up roll. It will be observed that the guide bar 112 connects the ends of the cam tracks 116. It serves to prevent the operator from improperly threading the toweling since the bar 112 causes the attendant to insert the end of the webbing over the roller 109, as indicated in Fig. 11, instead of under the same.

Thus, when the attendant pushes downward on the plate 106, the rollers 109 and 107 shift into the proper position for tensioning the web so as to cause the towel to be wound tightly and smoothly on the soiled towel take up roll. In the position of the parts when the threading operation is to be accomplished, the roll 109 is below the roll 107 so that the toweling takes a substantially straight path to the dirty towel take up roll when that roll is mounted in the position shown in Figs. 10 and 11. Thus little or no obstruction is offered by the parts of the tensioning assembly and the threading operation may be accomplished quickly and with little likelihood of mistake. When the plate 106 is pushed downward the roll 109 shifts to an uppermost position while the roll 107 is depressed. This causes the webbing of the towel to take a circuitous path and applies sufficient tension on the webbing to accomplish tight winding of the dirty towel.

It will be particularly noted, when the machine is in operation (Fig. 9) with tension on the webbing, that there is an upward force on the roller 107. For this reason a latch 121 is provided which is pressed by means of a spring 122 (Fig. 11) so that the margins of a groove 123 thereof engage a roller 124 carried by the side plate 23. Thus, when the roller 124 lies in the groove 123, the web tensioning assembly, generally indicated by the numeral 102, is latched in position. However, when desired the latch 121 may be cammed aside by manually raising the plate 106 against the action of the spring 122 to shift the plate 106 to the threading or towel loading position shown in Fig. 10. Further it is desirable to provide means for latching the web tensioning assembly in the threading position. This is accomplished by providing the latch with a second latch groove 126 which functions, in cooperation with the roller 124, to latch the web tensioning assembly 102 in the position shown in Fig. 11.

One important aspect of our invention lies in

the fact that the complete towel dispensing assembly, together with toweling, may be removed from the cabinet. Moreover, the machine, after rethreading the toweling, may be operated when the dispensing mechanism is out of the cabinet. This exposes the parts to view so as to enable complete observation of the functioning of the mechanism to permit such adjustment of the parts as may be required. In addition, the cabinet and towel dispensing assembly may be conveniently cleaned when the towel dispensing assembly is removed from the cabinet. Removal of the soiled toweling and loading the machine with fresh toweling is, of course, accomplished with the towel dispensing assembly in the cabinet.

Of particular advantage is the fact that the direction of feed roll rotation may be reversed upon opening the door. This latter fact permits the dirty towel to be quickly stripped from the take up roll, when desired, and permits the attendant to pull the towel backward partly or completely off the take up roll should the web be unevenly winding on the take up roll or should the web be kinked or wrinkled.

While we have shown the preferred form of our invention it will be apparent that various changes and modifications will suggest themselves to those skilled in the art, particularly in the form and relation of parts, without departing from the spirit of our invention as set forth in the appended claims.

We claim:

1. An apparatus for dispensing toweling comprising, in combination, a cabinet section having an opening, towel dispensing mechanism including a pair of operatively connected feed rolls supported within said cabinet section, a closure for said opening, and means actuated by said closure for preventing rotation of the feed rolls in one direction when the closure is closed.

2. An apparatus for dispensing toweling comprising, in combination, a cabinet section having an opening, towel dispensing mechanism supported within said cabinet section, said mechanism comprising a clean towel feed roll and a dirty towel feed roll operatively connected to said clean towel feed roll, a take up roll upon which the dirty toweling is accumulated as it is used, a closure for said opening, means actuated by said closure for locking the said rolls against rotation in one direction so as to prevent removal of the dirty toweling from the take up roll when the closure is closed, said means being released upon opening the closure so as to permit rotation of said feed rolls in both directions.

3. An apparatus for dispensing toweling comprising, in combination, a compartment having an upper wall for receiving a bolt of clean toweling and protecting it against dirt, a dirty toweling take up roll above said compartment, a pair of feed rolls with which the toweling contacts as it passes to the take up roll, one of said feed rolls being within the compartment and the other being above said upper wall, said upper wall being pivoted and so constructed and arranged that it presses the toweling against the feed roll which lies within the compartment.

4. An apparatus for dispensing toweling, a feed roll for toweling, a guide plate partly shrouding said feed roll, said guide plate being pivoted, means for normally shifting said guide plate about said pivot so as to press the toweling against said feed roll, a second pivoted guide plate lying above said feed roll and so constructed and ar-

ranged that it presses the toweling against the feed roll.

5. In an apparatus for dispensing toweling, a feed roll, a take up roll for dirty toweling driven by said feed roll, and means for tensioning the toweling so that it may wind tightly on said take up roll, said means comprising an upper member and a lower member, the toweling being threaded over the lower member and under the upper member, and means including a guide track for enabling shifting of said members after the threading has been completed to a position such that the lower member becomes the upper member.

6. An apparatus for dispensing toweling comprising, in combination, a cabinet section having an opening, towel dispensing mechanism including a pair of operatively connected feed rolls supported within said cabinet section, a closure for said opening, means including a ratchet wheel and a pawl for preventing rotation of the feed rolls in one direction when the closure is closed, and means for disengaging said pawl and ratchet wheel when the closure is open to permit rotation of the rolls in both directions.

7. An apparatus for dispensing toweling comprising, in combination, a cabinet having an opening, towel dispensing mechanism including feed roll means supported within said cabinet, a take up roll upon which the dirty toweling is accumulated as it is used, a closure for said opening, locking means for locking said roll means against rotation in one direction so as to prevent removal of the dirty toweling from the take up roll when the closure is closed, and means released by the closure for releasing said locking means when the closure is opened so as to enable rotation of said roll means in both directions.

8. In an apparatus for dispensing toweling, a feed roll for toweling and a pair of pivoted plates substantially shrouding said feed roll, said plates being constructed and arranged so that one of the plates presses the toweling against the roll substantially along the line where the toweling engages the feed roll while the other plate presses the toweling against the feed roll substantially along the line where the toweling leaves the said roll, and means associated with at least one of said plates for urging said plate into pressing position.

9. An apparatus for dispensing toweling comprising, in combination, a clean towel feed roll, a dirty towel feed roll, a support for a bolt of clean toweling, a dirty towel take up roll upon which the toweling is wound by the dirty towel feed roll, the web of toweling passing from the bolt around the clean towel feed roll and from thence to the take up roll, the web of toweling both entering and leaving the clean towel feed roll substantially at a tangent thereto and separate means for pressing the web of toweling into contact with the clean towel feed roll substantially along each line of tangency.

10. An apparatus for dispensing toweling comprising, in combination, a clean towel feed roll, a dirty towel feed roll, a support for a bolt of clean toweling, a dirty towel take up roll upon which the toweling is wound by the dirty towel feed roll, the web of toweling passing from the bolt around the clean towel feed roll and from thence to the take up roll, the web of toweling both entering and leaving the clean towel feed roll substantially at a tangent thereto, and separate means for pressing the web of toweling into contact with the clean towel feed roll substantially along each line of tangency, said last mentioned means being displaceable to enable convenient threading of the

web of toweling around the clean towel feed roll.

11. An apparatus for dispensing toweling comprising, in combination, a cabinet having an opening, towel dispensing mechanism including feed roll means supported within said cabinet, a closure for said opening, means for preventing rotation of the roll means in one direction when the closure

is closed and enabling rotation of the roll means in both directions when the closure is open, said means including an element on the dispensing mechanism movable by the closure upon the opening and closing thereof.

FRANK F. PULVER.

WILLIAM H. MATTHEWS.
